[57] **ABSTRACT**

The specification discloses a tool for temporarily sealing the end of tubing used in the construction of residential housing and buildings to allow the tubing to be tested for water leaks. The end of the tubing is crimped at a position close to but spaced from its end which is maintained open during the crimping process to form an open ended trough which then is filled with molten solder. The tool comprises a pair of movable members pivotally coupled together and having jaw portions with crimping means extending from one side thereof. A pair of handles are pivotally coupled to the opposite ends of the movable members for moving the jaw portions and the crimping means apart for allowing the end of a tube to be received between the crimping means and the jaw portions and for moving the jaw portions and the crimping means together for crimping the tube at a position close to but spaced from its end. A mandrel is carried by the tool and has an end portion located between the jaw portions for insertion into the end of the tube to maintain the end of the tube open when it is being crimped.

TOOL FOR SEALING END OF TUBING

BACKGROUND OF THE INVENTION

This invention relates to a process for temporarily and effectively sealing the end of tubing and a simple and effective tool for carrying out the sealing process.

In the construction of residential housing and small buildings with concrete slab type floors, copper tubing is buried in the concrete for water supply connections and is "stubbled up" at various places when the plumbing is "roughed in". It is necessary to temporarily seal the tubing at each place where it is stubbed up so that the system can be tested under normal city water pressure for leaks prior to pouring the concrete to form the slab foundation.

In the conventional sealing process, a "pliers-like" tool is employed to simply pinch or crimp the upper edge of the tubing to form a seam. After the tubing has been crimped, the upper marginal portions of the seam are soldered. In carrying out this process, however, it is difficult to obtain a reliable seal that will not leak or "blow out" when normal water pressure is applied. The problem is thought to be due to two factors. First, the conduit at its upper end, is ordinarily cut off with a roller disc type cutter which tends to leave a small inwardly extending burr. This burr prevents a good seam from being formed when the tubing is crimped at its upper end. Also, since the seam is at the extreme upper end of the tubing, difficulty is experienced in applying the solder to the seam.

SUMMARY OF THE INVENTION

It is the object of the present invention to provide a method of reliably sealing the end of tubing and a simple and effective tool for use for carrying out the sealing process.

In the sealing process, the tube is crimped at a position close to but spaced from its end while the end of the tube is maintained open to form an open ended trough. Molten metal, such as solder, then is applied into the trough to form an effective seal.

The tool comprises a pair of movable members including jaw portions with crimping means adapted to be moved apart for receiving the end of the tube and to be moved together for crimping the tube at a position close to but spaced from its end. A pair of handles are coupled to the members for moving the jaw portions apart and together. In addition, a mandrel is carried by the tool and has an end portion located between the jaw portions for insertion into the end of the tube to maintain the end of the tube open when it is being crimped.

In a further aspect, the tool comprises a pair of movable members, each including a rear end and a jaw portion at an opposite end thereof. Each jaw portion includes crimping means extending from one side thereof. Pivot means is provided for supporting the movable members for pivotal movement for allowing the jaw portions and crimping means to be moved apart and together. The pair of handles have first ends pivotally coupled together and to the rear ends of the movable members respectively.

In another aspect, the mandrel has a rear end opposite its end portion and which includes an elongated slot means formed therethrough. Pivot means extends through the elongated slot means and through the first ends of the handles for pivotally coupling the first ends

of the handles together and for maintaining the end portion of the mandrel centered between the jaw portions.

BRIEF DESCRIPTION OF THE DRAWINGS

FIG. 1 illustrates the end of a tube to be temporarily sealed;

FIG. 2 illustrates the end of a tube temporarily sealed in accordance with a prior technique;

FIGS. 3 and 4 illustrate the sequence of steps employed for sealing the end of a tube in accordance with the present invention;

FIGS. 5 and 6 illustrate the tool of the present invention employed in the process of crimping a tube at a position close to but spaced from its end;

FIG. 7 is an exploded view of the tool of FIGS. 5 and 6; and

FIG. 8 is a modified component of the tool of FIGS. 5-7.

DESCRIPTION OF THE PRIOR ART

Referring to FIG. 1, there is illustrated a short piece of copper tubing 21 which has been stubbed up in the construction of residential housing or small buildings,

as mentioned above, but which has not been sealed. The copper tubing may be conventional tubing having a diameter of $\frac{1}{2}$ inch, $\frac{3}{8}$ inch, or 1 inch. FIG. 2 illustrates the tubing of FIG. 1 which has been temporarily sealed in the conventional manner. In this sealing process, a pliers-like tool is utilized to simply pinch or crimp the upper end or edge 21a of the tubing to form a seam 23 which completely closes the opening 21b. After the tubing has been pinched and the seam 23 formed, the upper marginal portion of the seam is soldered. This sealing technique is unsatisfactory for the reasons mentioned above.

DETAILED DESCRIPTION OF THE INVENTION

Referring now to FIGS. 3-8 of the drawings, there will be described the process and tool of the present invention for sealing the end of tubing. Referring to FIGS. 3 and 4, in the present sealing process, the tube 21 is pinched or crimped at a position close to but spaced from its end 21a to form the seam 25. Crimping

may be carried out at a distance of about one-half inch from the upper end of the tube. During crimping, the end 21a of the tube 21 is held open and prevented from entirely collapsing to form a trough 21c. After the tube 21 has been crimped at 25 and the trough 21c formed, molten solder 27 is poured into the trough to seal the end of the tubing. The seam 25 prevents the molten solder from flowing downward while it hardens. Since there are no burrs within the tubing at the area where it is crimped, a neat, burr-free seam is provided by the crimping operation. Moreover, the resulting trough formed provides a zone for holding a generous quantity of solder along the seam whereby a very effective seal may be formed. After the tubing system has been tested for leaks, the upper end of the tube may be cut off below the seam 25 to allow connection to the plumbing.

Referring now to FIGS. 5-7, there will be described the crimping tool of the present invention for crimping tubing to form the configuration illustrated in FIG. 3. The tool comprises a pair of movable members, 31 and 33, pivotally coupled together by a bolt 35a and having jaw portions 37 and 39 at one end with crimping means

41 and 43 extending therefrom and which project inward toward each other. The members 31 and 33 have inwardly extending tab portions 45 and 47 through which the bolt 35a extends to space the jaw portions 37 and 39 apart to form a zone 49 therebetween.

Pivotedly coupled to the other ends of the members 31 and 35 are two handles 51 and 53 which may be moved apart to move the jaw portions 37 and 39 apart, as illustrated in FIG. 5, and which may be moved together to close the jaw portions, as illustrated in FIG. 6. Secured to the tool is a mandrel 49 having a narrowed or pointed end portion 51 which extends into the zone 49 formed between the jaw portions 37 and 39. The end portion 51 may be elliptical shaped in cross section, as illustrated in FIG. 7, or may be cone shaped, as illustrated at 51' in FIG. 8. The tip of the end portion 51 extends to a position short of the crimping members 41 and 43, as illustrated in FIG. 6. In the crimping process, the handles 51 and 53 are moved apart to open the jaws of the tool whereby the end of the tube 21 may be received between the crimping members 41 and 43 and received into the zone 49 between the jaw portions 35 and 37. In this position, the end 51 of the mandrel 49 will be located within the open end of the tube 21 and the crimping members 41 and 43 will be located at a position close to but spaced from the end of the tube. The handles 51 and 53 may then be moved together, thereby allowing the crimping members 41 and 43 to pince or crimp the tube at a position close to but spaced from its end. At the same time, the pointed end portion 51 of the mandrel prevent the end of the tube from collapsing and hence maintains the end of the tube open to form the trough portion 21c, as illustrated in FIG. 3. If the mandrel has a conical shaped end 51' as illustrated in FIG. 8, the configuration of the trough will be different from that shown in FIG. 3.

Referring to FIG. 7, there will be described in more detail the tool of the present invention. As illustrated, the mandrel 49 is a bifurcated member having two spaced and parallel arms 61 and 63 extending from the end portion 51. Formed through the arms 61 and 63 are two aligned and elongated slots 65 and 67 and two aligned apertures 69 and 71 located between the slots and the end 51. The tab portion 45 of member 31 has an aperture 45a formed therethrough while the tab portion 47 of member 33 comprises two spaced tabs 47a and 47b. Aligned apertures 47a' (not shown) and 47b' are formed through tabs 47a and 47b respectively. Members 31 and 33 are pivotally coupled together and to the mandrel 49 by inserting tabs 47a and 47b between the arms 61 and 63 and by inserting tab 49a between tabs 47a and 47b to align the apertures of the tabs with the apertures 69 and 71 of arms 61 and 63. Bolt 35a then is inserted through the aligned apertures of the tabs and arms and secured in place with a nut 35b.

The handles 51 and 53 have end portions 51a and 53a which are pivotally coupled together and to the movable members 31 and 33 respectively. As illustrated, the end 51a of handle 51 has two spaced flat end portions 81 and 83 which have a pair of outwardly located and aligned apertures 81a and 83a formed therethrough and a pair of inwardly located and aligned apertures 81b and 83b (not shown) formed therethrough. The end 53a of handle 53 also has single flat end portion 85 which has an outwardly located aperture 85a and an inwardly located aperture 85b formed there-

through. The member 31 has a flat end portion 91 with an aperture 91a formed therethrough and which is adapted to be fitted between the end portions 81 and 83 of the handle 51. The member 33 has two spaced flat end portions 93 and 95 which have aligned apertures 93a (not shown) and 95a formed therethrough. The handle 51 is pivotally coupled to member 31 by inserting flat end portion 91 of member 31 between the flat end portions 81 and 83 of handle 51 to align apertures 81a, 91a, and 83a. Bolt 101a is then inserted through the aligned apertures and secured in place by nut 101b. Handle 53 is pivotally coupled to member 33 by inserting the outward portion of flat end portion 85 of handle 53 between the flat end portions 93 and 95 of member 33 to align apertures 93a, 85a, and 95a. Bolt 103a then is inserted through the aligned apertures and secured in place by nut 103b. The handles 51 and 53 are pivotally secured together and to the mandrel 49 by inserting the inward portion of the flat end portions 81 and 83 of handle 51 between arms 61 and 63 and then inserting the inward portion of flat end portion 85 of handle 53 between the end portions 81 and 83 of handle 51 to align apertures 83b, 85b, and 81b together and with elongated slots 65 and 67. A bolt 105 then is inserted through these aligned apertures and slots and secured in place with a nut. With this arrangement, the bolt 105 may move up and down within the slots 65 and 67 as the handles are moved to their open and closed positions whereby the slots 65 and 67 act as guides to maintain the end portion 51 of the mandrel centered between the jaws 37 and 39 as the jaws are opened and closed.

I claim:

1. A tool for crimping a tube at a position close to but spaced from an end thereof and for forming an open ended trough portion at said end, comprising:
a pair of movable members including jaw members with crimping means adapted to be moved apart for receiving the end of a tube and to be moved together for crimping the tube at a position close to but spaced from its end,
a pair of handles coupled to said members for moving said jaw portions and said crimping means apart and together, and
a mandrel carried by said tool and having an end portion located between said jaw portions for insertion into the end of the tube to maintain the end of the tube open when it is being crimped.
2. The tool of claim 1 comprising:
pivot means for supporting said movable members for pivotal movement to allow said jaw portions and said crimping means to be moved apart and together,
said pair of movable members each including a rear end opposite its jaw portion,
said pair of handles having first ends pivotally coupled together and to said rear ends of said movable members respectively for moving said jaw portions and said crimping means, apart for allowing the end of a tube to be received between said crimping means and said jaw portions and for moving said jaw portions and said crimping means together for crimping the tube at a position close to but spaced from its end.
3. The tool of claim 2 wherein:

said mandrel has a rear end opposite its end portion and which includes an elongated slot means formed therethrough, and pivot means extending through said elongated slot means and through said first ends of said handles for pivotally coupling said first ends of said handles together and for maintaining said end portion of said mandrel centered between said jaw portions.

4. The tool of claim 3 wherein:

said pivot means which supports said movable members for pivotal movement extends through said movable members and through said mandrel.

5. The tool of claim 3 wherein:

said pivot means which supports said movable members for pivotal movement comprises a single pivot means extending through said mandrel and through said movable members,

said single pivot means is located at a position between said rear ends and said crimping means of said movable members,

said single pivot means and said pivot means which extends through said elongated slot means define a plane which extends midway between said two movable members, and

third and fourth pivot means located on opposite sides of said plane respectively, each of which pivotally couples the rear end of one of said movable members to the first end of one of said handles.

6. The tool of claim 5 wherein:

said movable members include tab portions extend-

5

10

ing toward each other with apertures formed therethrough,

said single pivot means extends through said mandrel and through said apertures formed through said tab portions for pivotally coupling said movable members together and to said mandrel.

7. The tool of claim 6 wherein said mandrel comprises:

a bifurcated member having two spaced arms extending from said end portion,

said arms having a pair of aligned elongated slots formed therethrough and a pair of aligned apertures formed therethrough,

said aligned apertures being located between said end portion and said aligned elongated slots,

said tab portions of said movable members and said first ends of said handles being located within the space formed between said two arms,

said single pivot means extends through said aligned apertures formed through said arms of said mandrel and through said apertures formed through said tab portions of said movable members for securing said movable members together and to said mandrel,

said pivot means which pivotally couples said first ends of said handles together extends through said elongated slots of said arms of said mandrel and through said first ends of said handles.
